UNITED STATES PATENT OFFICE.

JAMES M. PECKHAM, OF FALL RIVER, ASSIGNOR TO GEORGE DRAPER & SONS, OF HOPEDALE, MASSACHUSETTS.

SHUTTLE-GUARD FOR LOOMS.

SPECIFICATION forming part of Letters Patent No. 453,499, dated June 2, 1891.

Application filed January 7, 1888. Serial No. 260,069. (No model.)

To all whom it may concern:

Be it known that I, JAMES M. PECKHAM, of Fall River, county of Bristol, State of Massachusetts, have invented an Improvement in 5 Shuttle-Guards for Looms, of which the following description, in connection with the accompanying drawings, is a specification, like letters on the drawings representing like parts.

10 My invention relates to a shuttle-guard to be used on a loom for preventing the shuttle from being accidentally thrown off from the shuttle-race.

The shuttle-guards now commonly used consist of a wire or rod connected with the hand-rail or top bar of the lay, and the fastening of the shuttle-guard to said hand-rail is likely to injure the latter, especially if the fastening bolts or screws work loose in the bar of wood 20 of which said hand-rail is composed.

The object of the present invention is to produce a shuttle-guard that is securely fastened in proper position with relation to the shuttle-race, and is so located as to be more 25 efficient in guiding the shuttle and preventing the accidental deflection thereof than the shuttle-guards now commonly used.

The invention consists, essentially, in a shuttle-guard composed of a rod or wire provided 30 with eyes at each end that receive bolts or screws by which the said rod is securely connected with the shuttle-box or mouth of the guide, into and from which the shuttle is thrown, the said rod being provided with an 35 offset near one end in order not to interfere with the operation of the stopping device controlled by the filling-thread.

Figure 1 is a front elevation of a portion of the lay of a loom provided with a shuttle-guard embodying this invention; Figs. 2 and 40 3, a front elevation and plan view, respectively, of portions of the shuttle-guard detached; Fig. 4, an end elevation showing the positions of the lay and breast-beam of the 45 loom, and Fig. 5 a plan view of a portion of the parts shown in Fig. 4.

The shuttle-guard *a* forming the subject of this invention consists of a rod or wire of proper length to extend from one to the other 50 of the mouth-pieces *b* at the ends of the shuttle-race *c*, into and out from which the shut-

tle is thrown in the usual manner, the said mouth-pieces *b* being usually composed of cast-iron.

The rod or bar *a* is provided at each end 55 with eyes *a'* (see Fig. 2) to receive bolts or screws by which the said rod is fastened to the said mouth-pieces *b*, as shown at *b'* in Fig. 1, the said fastening being permanent and durable, owing to the durable nature of the 60 material of said mouth-pieces.

In order to provide for the proper operation of the weft-fork *d*, forming a portion of the usual weft-thread stop-motion device, the rod *a* is offset near one end, as shown at *a'*, and 65 thus accommodates the rising and falling movement of the end of the latch-lever *d* that takes place at the end of the beating-up movement of the lay.

The weft-fork *d* forms a portion of a well-known stop-motion device, its hook end *d'* operating with a part that controls the belt or clutch shipper by which the loom is stopped and started, and causing the said loom to be stopped if said lever remains in the position 75 shown in full lines, Fig. 4, when the pick of thread is beaten up by the lay. The other end of the fork is provided with a number of projections *d''*, which are so arranged as to receive between them a number of projections 80 *e* on the lay when the latter arrives at its extreme forward movement in beating up the filling-thread. The said projections *e* are commonly called the "grid," and when the filling-thread is intact, as indicated at *f*, Fig. 4, it is 85 interposed between the projections *e* and projections *d''*, so that the former, instead of entering between the projections *d''*, press the filling-thread against the said projections, and thus tip up the fork, as indicated in dotted 90 lines, Fig. 4, so that it does not act to stop the loom. If, however, the filling-thread breaks, so that it is not interposed between the projections *e* and the projections *d''*, the former pass between the latter and the lever is not 95 raised, and the loom is consequently stopped. The offset *a'* of the shuttle-guard passes wholly over the end of the fork *d* at the moment that it is raised by the action of the projections *e* and thread *f*, as indicated in dotted lines, Fig. 100 5. The shuttle-guard *a* by this construction may be placed very close to the shuttle-race,

and will assist in guiding the shuttle across the race and effectually prevents the shuttle from being thrown off from the shuttle-race. It will not cause wear or injury to any part 5 of the loom, as is sometimes the case when the shuttle-guard is fastened to the wooden hand-rail or top bar of the lay.

I claim—

A shuttle-guard for looms, composed of a 10 rod provided with eyes at each end and hav-

ing an offset near one end, substantially as and for the purpose described.

In testimony whereof I have signed my name to this specification in the presence of two subscribing witnesses.

JAMES M. PECKHAM.
